US00D543435S

(12) **United States Design Patent** (10) **Patent No.:** **US D543,435 S**
Roberts, III (45) **Date of Patent:** **** May 29, 2007**

(54) **DOOR LEVER**(75) Inventor: **Rockwood Theodore Roberts, III,**
Indianapolis, IN (US)(73) Assignee: **Schlage Lock Company**, Indianapolis,
IN (US)(**) Term: **14 Years**(21) Appl. No.: **29/247,545**(22) Filed: **Jun. 26, 2006****Related U.S. Application Data**

(63) Continuation of application No. 29/241,973, filed on Nov. 3, 2005, now abandoned.

(51) **LOC (8) Cl. .... 08-06**(52) **U.S. Cl. .... D8/308**(58) **Field of Classification Search** D8/300,
D8/301, 307-312, DIG. 3; D23/249-254;
D7/649; 16/110.1; 74/519, 543; 4/675-678

See application file for complete search history.

Primary Examiner—Paula A. Greene

(74) Attorney, Agent, or Firm—Michael Best & Friedrich
LLP(57) **CLAIM**The ornamental design for a door lever, as shown and
described.

DESCRIPTION

FIG. 1 is a perspective view of a door lever showing the new
design for a door lever;

FIG. 2 is a front elevation view of FIG. 1;

FIG. 3 is a bottom elevation view of FIG. 1;

FIG. 4 is a rear elevation view of FIG. 1;

FIG. 5 is a right side elevation view of FIG. 1; and,

FIG. 6 is a left side elevation view of FIG. 1.

The broken-line disclosure in the views is for illustrative
purposes only and forms no part of the claimed design.**1 Claim, 2 Drawing Sheets**# US D543,435 S
